WILLIAM L. MORRIS, OF CHICAGO, ILLINOIS, ASSIGNOR TO S. F. BOWSER & COMPANY, INCORPORATED, OF FORT WAYNE, INDIANA, A CORPORATION OF INDIANA.

CLARIFYING SYSTEM FOR OILS AND THE LIKE.

1,056,928.

Specification of Letters Patent. Patented Mar. 25, 1913.

Application filed May 31, 1910. Serial No. 584,097.

To all whom it may concern:

Be it known that I, WILLIAM L. MORRIS, a citizen of the United States, residing at Chicago, in the county of Cook and State of Illinois, have invented certain new and useful Improvements in Clarifying Systems for Oils and the Like, of which the following is a full, clear, and exact description.

The invention relates to clarifying systems for oils and the like, and apparatus adapted for use in connection therewith.

The primary object of the invention is to provide an improved system and apparatus for clarifying oils and the like comprising such apparatus as will enable oil or other liquids to precipitate their heavier impurities and being provided with improved means for bringing these impurities to some one or more predetermined points in the system where the impurities may be removed.

A further object of the invention is to provide, in a system of the described character for clarifying oils and other liquids, improved means whereby the clarified portion of the oils or other liquids returned as precipitation may be returned to the system, if desired, after being clarified.

The invention further consists in details of construction and arrangements of the various parts of the system, as hereinafter more fully described, shown in the accompanying drawing forming a part of this specification, and finally pointed out in the appended claims.

In the said drawing, Figure 1 is a view in elevation with parts in section and parts broken away to disclose the details of construction. Fig. 2 is a broken detail view illustrating the construction of the overflow 40 of the refuse tank. Fig. 3 is an enlarged perspective view of the diffuser at the lower extremity of the discharge leading into the refuse tank.

In Fig. 1 of the drawing, the complete system is shown including a reservoir in the form of gravity tank indicated by the reference character 10, which is designed to contain the initial supply of oil or other liquid which may be passed to an engine or engines or to any other desired mechanism or location where there may be a drip or return discharge, the oil main from the tank 10 being indicated by the reference character 11. The drip return main is indicated by the

reference character 12 and it leads to the drip receiving and precipitation tank 13. The drip receiving and precipitation tank 13 is provided with an overflow pipe 14 near the top thereof leading to the filter indicated by the reference character 15. The details of this filter are not shown but any suitable form of filter may be employed and it will be apparent that the construction of the same will be varied according to the character of the oil or other liquid to be used. The filter 15 discharges downwardly through pipe 16 into the drip receiving tank 17 entering the same at one side near the bottom thereof as illustrated. 18 is a pump which is shown diagrammatically and may be of any desired construction and operated either by hand or power. 19 is the regular discharge pipe within the drip receiving tank 17 and the intake 20 of the same is located preferably as illustrated somewhat above the bottom of the tank in order that the heavier portions of the drip at the bottom may not be disturbed by the outflowing discharge. This regular discharge pipe 19 is provided with a suitable control valve 21, and leads to the pump 18. Leading also to the pump 18 is the low down clean out suction pipe 22, the lower extremity 23 of which serves as an intake and is preferably adjacent a depression in the bottom of the tank 17, as indicated at 24. A convenient arrangement of the pipes within tank 17 is that illustrated in which the pipe 22 leads directly upward to the pump and the regular discharge pipe 19 is tapped into it at 25 above the valve 26 controlling the low down clean out. The pump 18 is provided with a discharge pipe as at 27 controlled by a suitable closing valve 28 and discharging upwardly into the gravity tank 10. The main refuse tank is indicated by the reference character 29, it being preferably a closed tank, as illustrated, of any suitable construction adapted to receive the dirty deposits from the other parts of the system. The precipitation tank 13 is provided with a draw-off 30 composed of hand operating valve 31 and discharging into a suitable drain, as indicated at 32, being preferably in the form of a funnel opening upwardly as illustrated and being provided with a discharge pipe 33 which is extended downward to near the bottom of the main refuse tank.

29 and is provided at its lower extremity with a diffuser or spreader as indicated at 34 which prevents agitation of the contents of the tank 29. The tank 29 is provided with a suitable draw-off pump of any desired character 35 which has an intake 36 in pump barrel 35^b, preferably near the bottom of the tank 29, as shown. 35^c indicates the pump or piston rod, 35^d the piston, and 35^e, 10 35^f the pump valves controlling the discharge 37 over the funnel shaped drain 32, the discharge 37 being at a point which will permit a suitable receptacle being placed under it to permit the dirty oil from the pump 15 to be received and removed and used in such service as it may be fitted for but not returned to the system again. The supply tank 10 is provided with a suitable draw-off pipe 38, which also discharges into the tank 29 over 20 funnel-shaped drain 32, as does the draw-off 39 from tank 17. The draw-off pipe 38 from the supply tank is controlled by a suitable valve as indicated at 40 and draw-off pipe 39 by valve 41. The upper and clearer 25 portion of the oil in the tank 29 when the tank becomes full is discharged back to the system again by passing over the overflow as indicated by the reference character 42 and into tank 17 through pipes 43 and 16.

30 In the operation of the improved system, as above described, the reservoir or gravity tank 10, the precipitation tank 13, the filter 15, the drip receiving tank 17, the pump 18, the main refuse tank 29 and its exhaust 35 pump 35 being in regular service, the oil passes from tank 10 through the outlet which is above the bottom thereof through the oil main 11 to the location where it is to be used or handled in any desired manner 40 or where drips are liable to occur. Drips are returned to the precipitation or settling tank 13 through the return drip main 12 preferably entering the tank 13 at a point considerably above the bottom thereof, as 45 indicated to prevent agitating impurities lying upon the bottom of the tank. The heavier impurities in the drip are precipitated in this tank and lie stagnant on the bottom until the drain pipe of this tank is 50 brought into service. By reason of the precipitation or settling which will take place in tank 13, the clearer oil will rise to the top of the tank as indicated at 50, the stagnant impurities being indicated by the reference 55 character 51 at the bottom of the tank. The top clear oil overflows and is discharged through pipe 14, through filter 15, whence it passes by gravity through pipe 16 to drip receiving tank 17 entering the same near the 60 bottom thereof.

The pump 18 may be operated to remove the clear oil from tank 17 through the intake 20 which is above the bottom of the tank as indicated, the oil passing through 65 pipe 19, valve 21 being open and valve 26

closed, and when the valve 41 is closed and valve 28 opened, the oil will be forced upwardly through pipe 27 and discharged into tank 10. The fact that the intake 20 within the tank 17 is above the bottom thereof, as 70 described, will prevent the precipitated impurities within the tank 17 being returned to the reservoir or gravity tank 10.

It will be apparent that in time during the normal operation of the system, the 75 tanks 10 and 17 will contain impurities in considerable quantities which will lie upon the bottoms of these tanks. When quantities of such impurities have accumulated the same may be removed by first removing the 80 clear oil from tanks 10 and 17, which is accomplished in the manner described through pipes 11 and 19 respectively. Then the sediment or impurities in tanks 10 and 17 may be delivered to the main refuse tank 29, 85 tank 10 being emptied through discharge pipe 38 by opening valve 40 and tank 17 may be emptied of its impurities by the closing of the valve 21 in discharge pipe 19, and valve 28 in pipe 27 which leads to 90 supply tank 10, opening valves 26 and 41 respectively whence the impurities will be received at the depressed portion 94 of tank 17 through intake 23 of discharge pipe 22 thence through pipe 39 and into drain 32 95 whence these impurities reach the interior of tank 29 through pipe 33 and spreader 34 at the bottom thereof, which, as described, provides to a considerable extent a non-disrupting inflow into tank 29. The funnel 100 shaped drain 32 which receives these discharges of impurities from tanks 10 and 17 may be protected with a suitable perforated plate or other form of screen, as a screen of woven wire, as indicated at 32^a. It will be 105 apparent that the precipitation tank 13 will also become very dirty due to impurities which will collect in the bottom thereof, as this tank receives the return drip through pipe 12. Provision is therefore made for 110 discharging the entire contents of this tank into the main refuse tank 29 through discharge pipe 30 controlled by valve 31, which discharge pipe likewise leads to drain 32 in the top of the main refuse tank 29. Thus 115 the main refuse tank 29 serves to receive all these deposits of impurities and by reason of its peculiar construction of spreader 34 as described at the bottom of drain discharge pipe 33, this tank 29 receives these deposits of impurities without agitating its contents. As already described, the upper and clearer portions of the oil in main refuse tank 29 overflows through overflow 42 and pipes 43 and 16 120 respectively into drip receiving tank 17 whence it is returned to the system should the demand for refuse oil unfit for use in the system and to be withdrawn by pump 35 be less than the quantity delivered to the main 125 130

refuse tank 29 through drains 30, 38 and 39 respectively.

If it is desired for any purpose to withdraw from the tank 29 portions of the oil discharged therein clearer than may be obtained through discharge pump 35, the tank 29 may be provided with draw-off cocks at suitable heights from the bottom thereof, as indicated at 60 and 61.

10 In order that the invention might be fully understood, the details of the preferred embodiment thereof have been thus specifically described but it is not desired to be limited to the exact details of construction shown 15 and it will be apparent that many modifications in the construction and arrangement of the various parts may be made by those skilled in the art without departing from the purpose and spirit of the invention.

20 I claim:

1. The combination in a clarifying system for oils and the like, of a reservoir, an oil main leading from said reservoir, a drip return pipe, a precipitation tank, a filter, a 25 refuse tank, means for discharging the impurities from said precipitation tank to the refuse tank, an overflow for discharging the clarified oil from the precipitation tank to the filter, means for removing the impurities from the refuse tank from a point near the bottom thereof, a drip receiving tank, an overflow near the top of the refuse tank for discharging the clarified oil to the drip receiving tank, means for discharging the 30 oil from the filter to the drip receiving tank, means for discharging the clarified oil from the drip receiving tank to the reservoir, means for withdrawing the impurities from near the bottom of the drip receiving tank and discharging the same into the refuse tank, and means for withdrawing the impurities from the refuse tank from near the bottom thereof.

2. The combination in a clarifying system for oils and the like, of a reservoir, an oil main, a drip return pipe, a precipitation tank, a drip receiving tank, an overflow near the top of the precipitation tank leading to the drip receiving tank, a filter interposed in the overflow between the precipitation tank and the drip receiving tank, means for withdrawing the impurities from near the bottom of the precipitation tank, a refuse tank into which said last mentioned 50 means discharges, an overflow in the refuse tank near the top thereof leading to the drip receiving tank, means for returning the clarified portions of the oil from the drip receiving tank to the system, means for discharging the impurities from near the bottom of the drip receiving tank to the refuse tank, and means for removing the impurities from near the bottom of the refuse tank and from the system.

3. The combination in a clarifying system

for oils and the like, of a reservoir, an oil main, a drip return pipe, a precipitation tank, a drip receiving tank, an overflow from said precipitation tank to the drip receiving tank, a refuse tank, means near the bottom of the precipitation tank for withdrawing the heavy impurities from near the bottom of the precipitation tank and discharging the same into the refuse tank, a discharge main leading from said drip receiving tank to the reservoir, a pipe provided with an intake above the bottom of the drip receiving tank for discharging the clarified portions of the oil within said tank into said discharge main, a second pipe provided with an intake near the bottom of the drip receiving tank for discharging the impurities from the drip receiving tank to the refuse tank, and a pump for discharging both the clear oil and the impurities through 75 the said pipes and the main respectively to the reservoir and to the refuse tank.

4. The combination in a clarifying system for oils and the like, of a reservoir, an oil main leading from the reservoir, a precipitation tank, a drip receiving tank, an overflow near the top of said precipitation tank discharging into said drip receiving tank, a refuse tank, means for emptying deposits from near the bottom of the precipitation tank into the refuse tank, an overflow from said refuse tank near the top thereof discharging into said drip receiving tank, means for returning clarified oil from said drip receiving tank to the reservoir, means for discharging the impurities from near the bottom of said drip receiving tank into the refuse tank, and means for withdrawing the impurities from the system by taking them from the refuse tank and from near 105 the bottom thereof.

5. The combination in a clarifying system for oils and the like, of a reservoir, an oil main, a drip return pipe, a refuse tank, a drip receiving tank, means for discharging the oil from the drip return pipe into the refuse tank, means for discharging clarified oil from near the top of the refuse tank into the drip receiving tank, suitable pumping means for discharging the clarified oil from 110 the drip receiving tank to the reservoir, suitable pumping means for discharging the impurities from near the bottom of the drip receiving tank into the refuse tank, and pumping mechanism for removing the impurities from near the bottom of the refuse tank and discharging the same from the system.

6. The combination in a clarifying system for oils and the like, of a reservoir, an oil main, a drip return pipe, a precipitation tank into which said drip return pipe discharges, a refuse tank, a drip receiving tank, overflows leading from near the top of each of said precipitation and refuse 125

130

tanks and discharging into said drip receiving tank, means for removing the impurities from near the bottom of said precipitation tank and said drip receiving tank 5 and discharging the same into the refuse tank, means for removing the clarified oil from a point above the bottom of the drip receiving tank and discharging the same into the reservoir, and means for discharging the heavy impurities from near the bottom of the refuse tank and removing the same from the system.

7. The combination in a clarifying system for oils and the like, of a reservoir, an oil main leading from the reservoir, a precipitation tank, a drip return pipe emptying into said precipitation tank, a refuse tank, a drip receiving tank, means for removing the heavy impurities from near the bottom 20 of the precipitation and drip receiving tanks and from near the bottom of the reservoir and discharging the heavy impurities from each of said tanks into the refuse tank, means for removing the heavy impurities 25 from near the bottom of the refuse tank and discharging the same from the system, and means for removing the clarified oil from each of the precipitation, refuse and drip receiving tanks and returning the same to 30 the reservoir.

8. The combination in a clarifying system for oils and the like, of a reservoir, an oil main leading from the reservoir, a precipitation tank, a refuse tank, and a drip receiving tank, a drip return pipe discharging into the precipitation tank, means for removing the clarified oil from a point above the bottom of the precipitation, refuse and drip receiving tanks and discharging the same into the reservoir, means for removing the heavy impurities from near the bottom of each of the precipitation and drip receiving tanks and from the reservoir and discharging the same into the refuse tank, 45 and means for discharging the heavy impurities from near the bottom of the refuse tank and removing the same from the system.

9. The combination in a clarifying system 50 for oils and the like, of a reservoir, an oil main leading from the reservoir, a refuse tank, means for conveying the drip from the oil main to the refuse tank, a drip receiving tank, and overflow near the top of the refuse tank, discharging into the drip receiving tank, pumping means adapted to remove the heavy impurities from near the bottom of the drip receiving tank and discharge the same into the refuse tank, pumping means 55 adapted to remove the clarified oil from the drip receiving tank and discharge the same into the reservoir, and pumping means for removing the heavy impurities from near 60

the bottom of the refuse tank and discharging the same from the system.

10. The combination in a clarifying system for oils and the like, of a precipitation tank, a drip return pipe discharging into said precipitation tank, a refuse tank, means for discharging the heavy impurities from the precipitation tank into the refuse tank, a drip receiving tank, means for discharging the clarified oil from the precipitation and refuse tanks to the drip receiving tank, means for removing the heavy impurities 75 from near the bottom of the precipitation and drip receiving tanks and discharging the same into the refuse tank, and means for removing the heavy impurities from the bottom of the refuse tank and discharging the same from the system.

11. The combination in a clarifying system for oils and the like, of a precipitation tank, a drip return pipe discharging into said precipitation tank, a refuse tank, means for discharging the heavy impurities from the precipitation tank into the refuse tank, a drip receiving tank, means for discharging the clarified oil from the precipitation and refuse tanks to the drip receiving tank, means for removing the heavy impurities 85 from near the bottom of the precipitation and drip receiving tanks and discharging the same into the refuse tank, means for removing the heavy impurities from the bottom of the refuse tank and discharging the same from the system.

12. The combination with a supply tank or reservoir and an oil main adapted for removing oil from near the bottom thereof in regular service, a precipitation tank, a drip return pipe emptying into said precipitation tank, a drip receiving tank, a refuse tank, means for withdrawing the heavy impurities from near the bottom of the precipitation and drip receiving tanks and from the bottom of the reservoir or supply tank and discharging the said heavy impurities into the refuse tank, means for returning the clarified oil from the drip receiving tank to the system, and means for removing the heavy impurities from near 110 the bottom of the refuse tank and discharging the same from the system.

In testimony whereof I have signed my name to this specification, in the presence of two subscribing witnesses, on this 27th day of May, A. D. 1910.

WILLIAM L. MORRIS.
